(57) **CLAIM**

The ornamental design for a wall-mounted bracket, as shown and described.

DESCRIPTION

FIG. 1 is a perspective view of a wall-mounted bracket showing my design;

FIG. 2 is another perspective view thereof;

FIG. 3 is an elevated front-facing view thereof;

FIG. 4 is an elevated rear-facing view thereof;

FIG. 5 is an elevated left-facing view thereof;

FIG. 6 is an elevated right-facing view thereof;

FIG. 7 is an enlarged top plan view thereof;

FIG. 8 is an enlarged bottom plan view thereof;

FIG. 9 is a perspective view thereof in its intended state of use;

FIG. 10 is an enlarged view of area 10 circumscribed in FIG. 2; and,

FIG. 11 is an enlarged view of area 11 circumscribed in FIG. 8.

The broken lines consisting of evenly spaced dash lines in the drawings depict portions of the wall-mounted bracket that form no part of the claimed design.

The broken lines consisting of short and long dash lines encircling the enlarged detail views are for annotative purposes that form no part of the claimed design.

The broken lines illustrated in FIG. 9 depict environment and form no part of the claimed design.

1 Claim, 11 Drawing Sheets
